CLAIM

The ornamental design for a barbell clamp converter, as shown and described.

DESCRIPTION

FIG. 1 is a top, and left perspective view of a barbell clamp converter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a perspective view of the open state of barbell clamp converter; and,

FIG. 10 is an enlarged view of portion 10 shown in FIG. 9. The evenly broken lines in the drawings disclose unclaimed portions of the barbell clamp converter only; the dash-dot broken lines disclose boundaries of the unclaimed isolated and enlarged views only; the broken lines in the drawings form no part of the claimed design.
